US0D1026352S

(12) United States Design Patent (10) Patent No.: US D1,026,352 S
(45) Date of Patent: * May 7, 2024

(54) LEASH WITH DUAL LOOP SAFETY ATTACHMENT

(71) Applicant: Alyson Rodges, Arroyo Grande, CA (US)

(72) Inventor: Alyson Rodges, Arroyo Grande, CA (US)

() Term: 15 Years

(21) Appl. No.: 29/784,832

(22) Filed: May 21, 2021

(51) LOC (14) Cl. 30-04

(52) U.S. Cl.

USPC D30/153

(58) Field of Classification Search

USPC D10/72; D29/101.1; D30/145, 152, 153

CPC A01K 25/00; A01K 27/00; A01K 27/001; A01K 27/002; A01K 27/003; A01K 27/004; A01K 27/005
